TRAIN DISPATCHING SYSTEM FOR
RAILROADSFrank Lamont Dodgson, Rochester, N. Y., as-
signer to General Railway Signal Company,
Rochester, N. Y.

Application April 29, 1927, Serial No. 187,508

20 Claims. (Cl. 246—3)

This invention relates to systems for dispatching trains from a central point through the agency of signal indications, and more particularly to means for indicating or reporting at the central control point the movement of trains at the different points along a portion of the railroad under control of the operator at that central point.

In connection with handling trains by signal indications from a central point, as distinctive from train orders, it is important that the operator have complete and accurate information with respect to the movement of trains under his control, their location, direction of movement, and time of passing certain points. To handle the trains efficiently, the operator should have complete information with respect to train movements, not only as to existing conditions, but also for a limited time in the past. The time at which a given train, traveling in a given direction, passes a given point is essential information to the operator, as well as the existing location or position of trains. Also, it is desirable that the past performance and existing status of train location be indicated or manifested to the operator in such a way as to enable him to show, as a reminder, contemplated meets or passes which he may forecast from time to time.

With these and other considerations in mind, one of the objects of the present invention is to provide an arrangement of circuits and devices of which the time of occupancy of a track circuit, which is ordinarily one end of a siding, may be indicated efficiently and economically by utilizing the same line wire employed for controlling the signals and for operation of the switch at that location. More specifically, it is proposed to utilize the interruption of the line circuit at a time when its energization is not necessary for operating a switch or clearing signals to transmit the indication of the presence of a train.

Another object of the invention is to devise a system of communicating and recording information concerning train movements in such a way that the operator has conveniently available at all times the necessary information with respect to the past performance and present status, of the location and identification of trains, the position of switches and indications of signals, and the like, including the factor of time, whereby the operator is enabled to handle the trains in his territory by signal indication alone in the most efficient manner and with minimum delay.

The organization and arrangement of instru-
55 mentalities and means permitting the operator to

exercise control over the indications of track-way and cab signals, and the position of switches, together with the transmission and recording of all the necessary data with respect to train operation and movement, provides for carrying out a novel method of dispatching trains. 5

Other objects, advantages and characteristic features of the invention will be in part apparent, and in part specifically pointed out, as the description progresses. 10

In the accompanying drawings, Fig. 1 illustrates diagrammatically with various conventional resignations, a simplified arrangement of control circuits for one end of a passing siding embodying the present invention; Fig. 2 shows 15 a modified arrangement of the circuits for the indicating means at the tower or central control point;

Fig. 3 shows a still further modified arrangement for controlling the indicating means in the 20 tower;

Fig. 4 shows a typical arrangement for one form of a graphic chart, constituting one of the instrumentalities employed in connection with the present invention; and 25

Fig. 5 shows a track diagram and representation of the control levers and indicating lamps.

In illustrating the invention, it has been shown for simplicity and convenience, adapted and applied to a train dispatching system of the type 30 disclosed in the application of S. N. Wight, Ser. No. 120,423, filed July 3, 1926, although it should be understood that this is merely a typical embodiment of the invention. According to this specific application or adaptation of the invention, a single track railway is contemplated, 35 equipped with the well known A. P. B. type of automatic block signals, with a single control wire, constituting with a common wire, a control circuit between the tower at the central control point and each end of each passing siding; this control circuit being polarized and providing all the necessary control for the operation and control of the switch machine and signals at that end of the siding, as well as the control of the indicating means of this invention. To avoid complication, various features of the circuits and devices for controlling the signals, the approach locking for the switch machines, and the like, 40 characteristic of the type of system disclosed in 45 said Wight application, have been omitted in showing the present invention; but it should be understood that all of these various auxiliary features may be, or are intended to be, employed with the present invention.

55

Fig. 1 shows at one end of a passing siding K, conveniently referred to as the east end, together with the signals 1, 1^a, 2, and 2^a for governing traffic in both directions into and between passing sidings, these signals being controlled in a manner shown and described in detail in said Wight application. The main track rails 3 and track rails 4 of the siding include insulated joints 5 segregating the usual detector track section, having track battery 6 and the detector track relay 2T. The track switch on the east end of this siding conveniently designated TSE, is preferably operated by a suitable power operated switch machine SM, although this track switch 10 may be operated by hand through the medium of the usual switch stand, if so desired. The switch machine includes suitable power operated means either pneumatic or electrical, and in the conventional arrangement shown includes a 15 series motor having an armature 10 and a field winding 11, which motor may be operated to its normal position through the normal wire N and to the reverse position through the reverse wire R through suitable pole changer contacts operated 20 by the switch machine mechanism in a manner as well understood by those skilled in the art, and as more fully described in the patent to Howe No. 1,466,903 granted Sept. 4, 1923, so that the operating circuits for this switch machine 25 need not be specifically considered. It may, however, be pointed out that the switch machine SM can not be operated unless the relay Z is energized in the proper direction and the approach locking relay ALR is energized. This approach locking 30 relay ALR may be controlled in a manner more clearly pointed out in the application of Wight heretofore referred to. Although no specific control circuits for the signals 1, 1^a, 2 and 2^a have been shown, these signals are controlled in accordance with traffic conditions ahead the position 35 the switch machine is assuming at the time, and the energized conditions of the control relay Z, in a manner as more specifically disclosed in the application of Wight heretofore mentioned 40 and this control has been conventionally shown by the contacts 90 and 91, and the dotted lines 92, 93, 94, 95 and 96.

With the switch machine SM shown there is associated a switch machine indicating relay 50 SMR, which is energized through the following circuit when the switch machine assumes either of its extreme positions, but is de-energized if the switch machine assumes an intermediate position:—beginning at the terminal B of a suitable source of energy, contacts 12—13—14 or contacts 55 15—16—17, depending upon whether the switch machine is in its reverse or its normal position respectively, wire 18, winding of the relay SMR to the common return wire C connected to the other side of said source of energy. This switch machine relay SMR by its front contact 19 controls a repeater relay RR through a circuit readily traced in the drawings. This repeater relay RR is slow-acting for reasons more clearly 60 pointed out hereinafter. The switch machine control circuits are controlled directly by the contact 54 of the mechanical stick relay MR having coils 55 and 56 and of which the contact 54 remains in the position to which it has last been actuated.

The dotted rectangle T represents a tower located a considerable distance from the siding K under consideration. In this tower there may be located a large number of levers for controlling

the signals and switch machines at the ends of various passing sidings, of which the lever L only has been shown. The equipment for one unit in the tower embodying the present invention also includes an indicating relay IR, which is connected in series with a line circuit heretofore mentioned, and controls the illumination of an indicating lamp I, which is controlled in a manner which will appear when the operation of the system is taken up.

Operation.—It should be noted that when the lever is in its normal neutral position that the relay Z is de-energized and its neutral contacts 20 and 90 are in the retracted position, so that no current can flow to the mechanical stick relay MR even though the polar contact 21 assumes one or the other extreme positions. Let us now assume that the operator in the tower wishes traffic to proceed over the main track and in order to do so moves his lever L to the right, and thereby completes a circuit which may be traced as follows:—beginning at the battery 22, wire 24, lever L, wire 25, winding of the line relay LR, line wire 26, contact 27 of the repeater relay RR, wire 28, contact 29 of the switch machine relay SMR, wire 30, winding of the relay Z, wire 31, front contact 32, of the detector track relay 2T, common return wire 33, back to the battery 22. The completion of this circuit causes the polar contact 21 to remain in its normal right hand position and causes the neutral contact 20 to be picked up, and with the relay Z energized to this position current may flow to the winding 55 of the relay MR, but since the contact 54 already assumes the right hand position no particular effect is produced. The energization of the relay Z through closure of the contact 90 permits clearing of a main track signal, so that traffic may move over the main track in response to clearing of such signals in a manner and by circuits as clearly pointed out in the application of Wight to which reference has been made. In this connection it is desired to point out that the flow of current in the circuit just traced not only places the relay Z in its energized condition but also energizes the indicating relay IR and causes the contact 34 to assume the raised dotted position. If now a train enters upon the detector track circuit in response to the clearing of one or the other of the signals 1 or 2 the detector track relay 2T will assume its de-energized position and in so doing will cause the cleared signal to move to the stop position through the usual control provided between the detector track relay and signal in question. Also, this entrance of a train upon the detector track circuit causes the contact 32 of the track relay 2T, to drop, thereby de-energizing the relays Z and IR and thereby completing a circuit for the indicating lamp I which may be traced as follows:—beginning at the battery 22, wire 24, lever contact L, wire 35, back contact 34 of the indicating relay IR, wire 36, indicating lamp I, wire 37 through the common return wire 33 connected to the side of battery 22. The indicating lamp I will remain energized so long as the detector track circuit is occupied, or in other words, a continuing indication is received at the tower as to the condition of the detector track circuit relay located at a distant siding. As soon as the train passes off of the detector track circuit the contact 32 of the detector track relay 2T is again closed thereby causing re-energization of the relay Z and IR and by reason of the raising of contact 34 of

the indicating relay IR the indicating lamp I is extinguished.

Let us now assume that the operator in the tower wishes a west bound train to enter the siding of the passing siding K. In order to do so the switch machine SM must be operated to the reverse position and in order to accomplish this the operator must act and either put the signals to stop or operate the switch machine before the approach locking relay ALR is de-energized due to an approaching train for reasons given in said Wight application. Let us assume that the operator acts in time and moves the lever L to the left hand position before the approach locking relay ALR is de-energized due to the approaching train. Movement of the lever L to the left hand position closes the following circuit:—beginning at the battery 23, wire 38, contact of the lever L in its left hand position, wire 25, winding of the line relay LR, wire 26, contact 27 of the repeater relay RR, wire 28, front contact 29 of the switch machine relay SMR, wire 30, winding of the relay Z, wire 31, front contact 32 of the track relay 2T, common return wire 33, connected to the other side of the battery 23. The completion of this circuit causes current of reverse polarity to flow in the winding of the relay Z, thereby causing the relay Z to be energized to the reversed or left hand position and also causes the indicating relay IR to assume its energized position. With the relay Z energized to its left hand position, the following circuit for the coil 56 of the relay MR is completed:—beginning at the terminal B, wire 40, front contact 41 of the relay ALR, wire 42, front contact 20 of the relay Z, wire 44, polar contact 21, wire 58, coil 56 of the relay MR, to the other terminal C. This operates the contact 54 to the left hand dotted position and causes the following circuit for operating the switch machine to be completed:—beginning at the terminal B of a suitable source of energy, contact 54 in its left hand dotted position, the reverse control wire R of the switch machine SM pole changer contacts 45, 46 and 47, wire 48, field winding 11 of the switch machine motor, wires 49 and 50, pole changer contacts 51, 52 and 53, armature 10 of the switch machine motor to the common return wire C connected to the other side of said source of energy. The flow of current in this circuit causes the switch machine to be moved to the reverse, or take siding position, and when it has been moved to this position and the relay Z is still energized, the take siding signal 1A will be cleared for reasons pointed out in the application of Wight by the reason of the control illustrated by the dotted lines 92 and 94. It should be noted that when operation of the switch machine was started the switch machine relay SMR was de-energized. De-energization of the relay SMR causes the contacts 19 and 29 to assume the retracted position thereby de-energizing the relay IR at the tower and causing the indicating lamp I to be lighted. De-energization of the relay SMR however also causes the repeater relay RR to be de-energized, and after a time by reason of its slow action causes the contact 27 to assume its retracted position, and this again causes the relay IR to be energized through the line circuit heretofore traced with the exception that the wire 28¹ is substituted for the wire 28. When the switch machine has assumed the reverse position the switch machine relay SMR is again energized, thereby raising its contact 29 and again opening the line circuit and de-energizing the indicating relay IR and caus-

ing the indicating lamp I to be again illuminated. Energization of the relay SMR, however, also picks up the contact 19 and after a short interval of time causes the repeater relay RR to raise the contact 27 and again causes energization of the line relay IR and causes extinguishment of the indicating lamp I. In other words, when the switch machine SM is operated the indicating lamp I is momentarily energized when the switch machine is started and is again momentarily energized when the switch machine has completed its operating stroke. The approach of the train under consideration when moving into the siding of passing siding K will cause the indicating lamp I to be energized so long as this train occupies the detector track circuit for reasons heretofore given.

Modified indicating means at tower (Fig. 2).— In some cases it is desirable to be able to store the indication, so to speak, that is, provide means whereby if the indicating lamp I has once been energized it will either remain energized in spite of the movement of the train off of the detector track circuit, or another substitute lamp will be energized thereafter until this substitute lamp has been manually extinguished. Referring to Fig. 2 such a substitute lamp I^a has been shown. In Fig. 2 of the drawings the control for the line circuit including the line wire 26 the indicating relay IR and the indicating lamp I, is the same as that shown in Fig. 1 and for this reason the component parts thereof have been given like reference characters. In addition to the indication relay IR there is provided in the tower T shown in Fig. 2 of the drawings a stick indicating relay SR. This stick relay SR preferably has operating characteristics such that if the lever L is moved to either the right or left hand position for the purpose of energizing the line wire 26 the stick relay SR will not be able to pick up during the short time that the contact 60 of the indicating relay IR is still in its retracted position after energization of the line circuit 26. In other words, if the lever L is moved to the right hand position the flow of current in the line circuit and indicating relay IR picks up the contacts 34 and 60 of this relay so that both the lamps I and I^a are extinguished. If now, the line circuit including the wire 26 is opened at a point such as at the contact 32 of the track relay 2T (see Fig. 1) the indicating relay IR will be de-energized, thereby illuminating the indicating lamp I for reasons heretofore given, and also the stick relay SR is energized because it is connected in multiple with the lamp I. As soon as the stick relay SR has assumed its energized position its stick contact 61 is closed thereby closing a stick circuit for same which may be traced as follows:—beginning at the battery 22, wire 24, lever L, wire 62, normally closed push button contact 63, wire 64, stick contact 61 of the relay SR, wires 65 and 66, winding of the relay SR, wire 67, switch 68, wire 69 to the common return wire 33 connected to the other side of the battery 22. Energization of the stick relay SR will of course also close the front contact 70 of this relay and thereby close a circuit for the supplemental indicating lamp I^a, which may be readily traced in the drawings. It should be noted that after the train has passed off of the detector track circuit and the indicating relay IR is again energized, that the indicating lamp I will be extinguished but the stick relay SR will remain stuck up and consequently the supplemental indicating lamp I^a will remain illuminated. The stick relay SR and in turn the indicating lamp

I^a may be de-energized by momentary depression of the push button contact 63, because depression of this contact opens the stick circuit for the relay SR, and this stick circuit will not be re-established 5 upon return of the push button contact 63 to normal after the stick relay SR has once assumed its de-energized position. Similarly the return of the lever L to the neutral position will drop the stick relay SR and extinguish the supplemental 10 indicating lamp I^a . If the supplemental stick indicating feature is not desired at any time, the operator may open the switch 68 and thereby avoid operation of the stick relay SR and a stick 15 indication in response to operation of this relay SR.

Modification (Fig. 3).—In Fig. 3 of the drawings has been shown a tower equipment very similar to that shown in Fig. 2, except that only one indicating lamp is shown which may be caused 20 to function as the indicating lamp I shown in Figs. 1 and 2 or may be caused to function like the indicating lamp I^a shown in Fig. 2. In the arrangement shown in Fig. 3 the lever L has operatively connected thereto an additional contact L^1 . It readily appears that if the lever L and its contacts L^1 are moved to either extreme position that the indication relay IR will be picked up for reasons heretofore given, and that de-energization of the indication relay IR will 25 cause the stick relay SR¹ to be picked up through the following circuit, providing the manually operable switch 68¹ is closed:—beginning at the battery 71, wires 72, contact L^1 of the lever L, wire 73, back contact 74 of the indicating relay 30 IR, wires 75 and 76, winding of the stick relay SR¹, wire 77, manually operable switch 68¹, wires 78 and 79, back to the battery 71. With the stick relay SR¹ once energized it will be stuck up through the following circuit:—beginning at the battery 35 71, wire 72, contact L^1 of the lever L, wires 73 and 80, stick contact 81 of the stick relay SR¹, wires 82 and 76, winding of the stick relay SR², wire 77, contact switch 68¹, wires 78 and 79 back to the battery 71. Also, it should be noted that the 40 lamp 1^b will be illuminated when the stick relay SR¹ is energized, because it is connected in multiple therewith, and further, it should be noted that the indicating lamp 1^b is energized even though the manually operable switch 68¹ is open, 45 this by reason of the following circuit:—beginning at the battery 71, wire 72, contact L^1 of the lever L, wire 73, back contact 74 of the line relay LR, wires 75 and 83, indicating lamp 1^b , wires 84 and 79, back to the battery 71. Or in other 50 words, if the manually operable switch 68¹ is left open the indicating lamp 1^b gives indications the same as do the indicating lights I in Figs. 1 and 2, and if the switch 68¹ is maintained closed the indicating line 1^b will function like the indicating 55 light I^a in Fig. 2, that is, will if once illuminated remain illuminated until either the lever L is restored to the intermediate or neutral position or the switch 68¹ is manually opened.

A characteristic feature of the indicating means 60 is that the indication of the occupancy of the detector track circuit, and also the operation of the switch machine, are obtained by controlling the same line circuit employed for governing the operation of the switch machine and the indications of the trackway signals. This is based on the premise 65 that this control line circuit may be deenergized when and so long as a train occupies the detector track circuit, without interfering with the use of this line circuit for the control of the signal 70 indications, because while said detector track 75

circuit is occupied, the signals to be cleared by energization of said line control circuit are necessarily at stop. In other words, a single control line circuit is utilized for different functions at different times. Likewise, the interruption of the control line circuit, to provide the indications of switch machine operation, do not interfere with the function of the line circuit and maintain signals clear, because these signals should be at stop during the operation of the 10 switch. 15

Graphic chart.—From the foregoing explanation, it can be seen how the operator is advised by the lighting of the lamps I, for each end of each siding when a train enters the detector track 20 circuit for that siding end, and also when the train clears that detector track circuit. The lighting of this indicating lamp, or the operation of what other equivalent indicating means is employed, does not of itself inform the operator the 25 direction in which the train is traveling, or the specific train number of designations of that train. While the operator may keep in mind, as a sort of mental process, a location and direction of movement of the different particular trains in his territory from time to time, and consequently be able to identify the lighting of a particular indicating lamp I with a particular train traveling in a certain direction, it is obviously desirable 30 to assist the operator and aid in avoiding mistakes by making it unnecessary for him to rely upon his memory entirely. In accordance with this invention, it is proposed to provide a graphic chart, which is in a sense a recording or indicating means manually operated by the dispatcher, so arranged and organized that it may be manipulated in conjunction with the control levers and the indicating lamps so as to provide all the necessary data for the dispatcher and further facilitate his manipulation of the whole 35 system in a way to minimize mistakes. 40

This graphic chart may take various specific forms; and only one typical arrangement has been illustrated in Fig. 4. At the top of the chart are blanks for data about the number and 45 make-up of the trains. The vertical lines show divisions of time indicated by the figures at the top. Horizontal lines represent the ends of the sidings at the places designated by the names. These horizontal lines may be equally spaced on 50 the chart, irrespective of the distance between the sidings; or the length of the sidings; or, if desired, these horizontal lines may be spaced apart approximately to scale in accordance with the distance along the track. Obviously, the 55 chart may be arranged so that horizontal lines indicate time and vertical lines the ends of the sidings.

In using this chart, it is contemplated that the operator, whenever any one of the indicating 60 lamps lights, will make a short vertical line, as indicated by the reference number 100 at the proper point on the chart corresponding to the existing time and end of the siding corresponding to the light lighted. For example, the mark 65 designated 100 indicates that a train entered the detector track circuit at the west end of the siding at Luckey at 11:52. By joining these marks, the operator obtains a graphic record of the train performance. 70

As each train comes onto the portion of track under the control of the operator, he is advised of the number of this train and its make-up, and starts on the chart a line for this particular train number. For example, referring to Fig. 4, 75

train No. X140 was reported ready and entered the territory of the operator at Stanley Yard at 12:02. As this train advances and causes lighting of the several indicating lamps, the operator 5 is able to make a mark on the chart to show the time this train passed each detector track circuit, and by joining these marks obtains a graphic record of the train performance.

The particular markings on the chart, at Fig. 10 4 are intended to represent the beginning of a chart record made by an operator coming on duty at about 12 o'clock noon. This operator coming on duty copies from the record chart of the previous operator, or observes the manipulation 15 of the system for a short time, enough to familiarize himself with the existing location of trains. For convenient reference in discussing the particular marking shown on the chart in Fig. 4, there has been shown in Fig. 5 a typical 20 arrangement of the track diagram, with its levers and indicating lights, for the section of railroad covered by the chart of Fig. 4; and Fig. 5 shows how the trains, as shown by the chart of Fig. 4, would be located on the railroad at the 25 selected time of 12:10. Referring to Fig. 4, and starting at the top of the chart along the vertical line indicating 12:10, it will be noted that according to the chart, train X140 eastbound left the east end of the siding at Stanley Yard at 12:04 30 and is now somewhere between Stanley Yard and Stoney Ridge, as shown in Fig. 5. The markings at Pemberville indicate that eastbound train No. 84 arrived at the west end of the siding at Pemberville at 12:06, and the train conductor 35 was informed by the operator over the telephone that he could do switching until 12:16, this information being shown by the dotted line marked "S" terminating at the vertical line representing 12:16. The chart also shows that train No. 59 40 westbound left Woodside at 12:04 and is now on its way toward Pemberville. As shown by the chart, and also in Fig. 5, train No. 44 entered the detector track circuit at the west end of the siding at Hatton at 12:10; and the work extra WE 45 is on the siding at Hatton, having returned ahead of the time assigned to it, indicated by the dotted lines, to work between Norris and Hatton.

The chart also provides a convenient place for 50 making notations of contemplated meets, instructions issued, and the like to guide the operator in the manipulation of his levers. For example, after making a survey of the probable 55 train performance, and having concluded that the work extra WE will be free to work between Hatton and Norris until 1:10, the operator can note this decision by the dotted lines designated 101. As another illustration, the operator may put the notation of the figures 84 above a horizontal line with the figures 59 beneath, as shown 60 near the siding Pemberville, to indicate to him that train No. 84 is to go in the siding at Pemberville for train No. 59. Notations and memoranda of other kinds can be readily adopted by the operator to take care of various other contingencies and conditions that may arise.

A graphic chart, made as described, affords 65 the operator all of the necessary or desirable information with regard to the location and movement of trains, past, present, and contemplated in the future, as well as affording a permanent record of train performance. In making the marks on the chart, the operator of course follows the indicating lamps. Whenever a lamp lights, he makes a mark at the place corresponding to 70 that lamp at the proper time; and by associating

this mark with other marks already made, he is able to identify positively the number of the train and its direction of movement causing that particular lamp to light. It is good practice for the operator to make the mark on his chart, then 5 move the corresponding lever and put out the light, this being a check to show that he has recorded the train movement.

The positions of the levers show what signals have been cleared and how the switches are set. 10 It is considered to be good practice for the operator to keep at least two levers moved ahead of each train. For example, referring to Fig. 5, when the lever L¹ was restored to the neutral position to put out the lamp lighted by the passage of train X140, the operator should move lever L³, assuming of course that this train X140 is to go past the siding at Stoney Ridge. It may be explained here that the righthand position of the levers is assumed to correspond with the 15 normal position of the switch, the direction of traffic being set up by the sequence in which the levers are operated as previously explained. Continuing the explanation of the significance of the lever positions, and still referring to Fig. 5, 20 25 lever L⁶ being in the lefthand or reverse position shows that train No. 84, when it returns after the expiration of the switching time (see Fig. 4), will go onto the siding; whereas lever L⁷ being to the right or normal position, shows that train 59 30 35 will keep on the main track. Thus, the levers are already in position for a meet of trains 84 and 59 at Pemberville; and the operator has nothing further to do until one or the other of these trains causes lighting of an indicating lamp. If train 84 arrives first, as it should according to the schedule, the lamp for the lever L⁶ lights; and after recording this on the chart, the operator may put the lever L⁶ to the normal 40 position, clearing the signals for train 59. When 45 train 59 arrives and lights the lamp for lever L⁷, the operator after noting this fact, may reverse the lever L⁷ as soon as train 59 has cleared the detector track circuit, thereby permitting train 84 to come out. The operator should operate 50 levers L⁵ and L⁸ as soon as proper to do so, so as to keep two levers shifted ahead of each train. In operating the lever L⁵, the operator is guided by the notation on his chart (see Fig. 4) to the effect that train 59 is to pass train X140 at Stoney 55 Ridge so that he knows the levers L⁵ and L⁴ should be operated to the normal position.

Numerous other examples could be given to show how the position of the levers, the indicating lamps, and the graphic chart of Fig. 4 all serve in 60 providing the operator with the necessary information for handling the trains. Each of these instrumentalities performs its part, and each is essential to practicing the method of train dispatching constituting this invention. The lines and 65 marks on the chart, for a given time, show the position of each train. The position of the levers show how the switches and signals have been operated to allow the trains to move. If the chart is drawn approximately to scale with reference to the distances along the track, lines of the proper slope, based upon the running time of a given train, and started at the right point at one siding will give an approximate indication of the time of 70 arrival of that train at the next indicating point. If desired, suitable markings on the chart may be employed to indicate the time of operation of the switches or of the levers. In short, the chart may be used as a record of various kinds of data as 75 may be desired.

Possibly it is still not clear in the mind of one reading the foregoing description as to how a train standing on the side track of a passing siding may be distinguished from one standing or running on the main track of such passing siding. To make this more clear I wish to point out that when a train enters a side track two short lines in the form of a letter L are drawn at that end of the siding where such train enters as indicated at 6 minutes past noon at the west end of the passing siding Hatton; whereas for a train entering the main track a short vertical line only is made as indicated at 11 minutes past noon at the east end of this same passing siding. When a train leaves the main track of a passing siding a similar vertical line is made and a diagonal line is drawn to connect the two vertical lines as indicated at Pemberville 11:56-11:58, at Luckey 11:52-11:56 and at Stanley Yard 2 to 4 minutes past noon. Similarly in the case of a train leaving a siding a vertical line is drawn as indicated at the east end of Woodside at 4 minutes past noon, and this vertical line is then connected up to the L shaped entry made at 11:50 by a horizontal line (as distinguished from a diagonal line) so as to indicate that the train in question occupied the siding. In other words, a train passing over a switch in its normal position is indicated by a vertical line, and a train passing over a switch in the reversed position is indicated by an L-shaped line (in this case the normal position of the switch is the main track position and the reverse position is take-siding position).

While certain specific apparatus and circuits, and certain particular steps in the method of train dispatching, have been shown and explained, it should be understood that the invention is not limited to the specific illustrations, and that various changes, additions and modifications may be made without departing from the spirit or scope of the invention.

What I claim is:-

1. In a dispatching system, the combination with a siding, a switch machine for operating the track switch at one end of said siding, a detector track circuit at one end of said siding, signals governing traffic over said track switch, a control relay for controlling said switch machine and signals, a line circuit controlled from a distant control point, manually operable means at said control point for energizing and deenergizing said line circuit to control said relay, means opening said line circuit so long as said detector track circuit is occupied and when operation of said switch machine is initiated, and an indicator at said distant controlled point lighted so long as said line circuit is open at said siding and said manually operable means is in its operated position.

2. Control and indicating apparatus for controlling the clearance of a distant signal and for indicating the passage of a train by such signal comprising; a local tower housing a control lever having a contact; a distant signal; a track circuit adjacent said signal including the usual track relay; a control relay near said signal which if energized permits clearing of said signal if traffic conditions in advance thereof are clear; an indicating relay at the tower; a circuit including said lever contact, said indicating relay, a contact closed when said track relay is energized and a source of energy in series; whereby said indicating relay is de-energized so long as said track relay is de-energized and said lever contact is in a position to close said circuit at the tower end; and means giving a continued stored indication if said

indicating relay has been once de-energized which continues until manually canceled.

3. A control and indicating apparatus for controlling the clearance of a distant signal and for indicating the passage of a train by such signal comprising; a local tower housing a control lever having a contact; a distant signal; a track circuit adjacent said signal including the usual track relay; a control relay near said signal which if energized permits clearing of said signal if traffic conditions in advance thereof are clear; an indicating relay at the tower; a circuit including said lever contact, said indicating relay, a front contact closed when said track relay is energized and a source of energy in series; whereby said indicating relay is de-energized so long as said track relay is de-energized and said lever contact is in position to close said circuit at the tower end; another relay which has a pick-up circuit including a back contact of said indicating relay and has a stick circuit including its own front contact and a normally closed manually operable circuit closer; and indicating means rendered active if said another relay is in its energized condition; whereby said indicating means continues to give an indication after said indication relay has been once de-energized, even though only momentarily de-energized, until said manually operable circuit closer is opened.

4. A system for controlling the operation of switches and signals and also indicating train movement over one line circuit comprising; a polarized control relay, a track relay, an indicating relay, a switch machine and circuit controlling means automatically opened momentarily when said switch machine starts or completes its cycle of operation; a circuit including in series said indicating relay, said circuit controlling means, said control relay and means opening said circuit so long as said track relay is deenergized; manually operable control means for energizing said line circuit with current of either of opposite polarities or de-energizing it; and an indicating means operated by said indicating relay and effective while said line circuit is open and said control means is in position to energize it.

5. In a dispatching system, the combination with a local dispatcher's office and a railway system having a distant track switch; of a switch machine for operating said track switch; a detector track circuit associated with said track switch and including a track relay; a signal for governing the movement of trains over said track switch; a control relay for controlling said track switch and signal; a source of current in said dispatcher's office; an indicating relay in said dispatcher's office; a circuit including said source, said control relay and said indicating relay in series; means in said circuit at said distant track switch for opening said circuit momentarily upon operation of said switch machine and opening said circuit continuously during occupancy of said track circuit to effect a corresponding continuous deenergization of said indication relay so long as said track circuit is occupied; and indicating means controlled by said indicating relay.

6. In a dispatching system, the combination with a local dispatcher's office and a railway system having a distant track switch; of a switch machine for operating said track switch; a detector track circuit associated with said track switch and including a track relay; a signal for governing the movement of trains over said track switch; a control relay for controlling said signal; stick control means controlled by said control re-

- lay for controlling said switch machine; a source of current in said dispatcher's office; an indication relay in said dispatcher's office; a circuit including said source, said control relay and said indicating relay in series; means in said circuit at said distant track switch for opening said circuit momentarily upon operation of said switch machine and opening said circuit continuously during occupancy of said track circuit to effect a corresponding deenergization of said indication relay; and indicating means controlled by said indicating relay.
7. In a dispatching system, the combination with a local dispatcher's office and a railway system having a distant track switch; of a switch machine for operating said track switch; a detector track circuit associated with said track switch and including a track relay; a signal for governing the movement of trains over said track switch; a control relay for controlling said signal; a source of current in said dispatcher's office; an indicating relay in said dispatcher's office; a circuit including said source, said control relay and said indicating relay in series; means in said circuit at said distant track switch for opening said circuit momentarily upon operation of said switch machine and opening said circuit continuously during occupancy of said track circuit to effect a corresponding deenergization of said indicating relay; indicating means controlled by said indicating relay, and means for maintaining said indicating means active if once rendered active until manually restored.
8. In a dispatching system, the combination with a local dispatcher's office and a railway system having a distant track switch; of a switch machine for operating said track switch; a detector track circuit associated with said track switch and including a track relay; a signal for governing the movement of trains over said track switch; a control relay for controlling said signal; a source of current in said dispatcher's office; an indicating relay in said dispatcher's office; a circuit including said source, said control relay and said indicating relay in series; means in said circuit at said distant track switch for opening said circuit momentarily upon operation of said switch machine and opening said circuit continuously during occupancy of said track circuit to effect a corresponding deenergization of said indication relay; indicating means controlled by said indicating relay, and means for maintaining said indicating means active if once rendered active until manually restored.
9. In a dispatching system, the combination with a local dispatcher's office and a railway system having a distant track switch; of a switch machine for operating said track switch; a detector track circuit associated with said track switch and including a track relay; a signal for governing the movement of trains over said track switch; a control relay for controlling said track switch and signal; a source of current in said dispatcher's office; an indicating relay in said dispatcher's office; a circuit including said source, said control relay and said indicating relay in series; means in said circuit at said distant track switch for opening said circuit momentarily upon operation of said switch machine and opening said circuit continuously during occupancy of said track circuit to effect a corresponding deenergization of said indication relay; and two indicators controlled by said indicating relay one indicator of which is rendered effective so long as said indicating relay is deenergized and the other indicator of which is effective until manually released even though said indicating relay has been energized in the meantime.
10. In a dispatching system, the combination with a local dispatcher's office and a railway system having a distant track switch; of a switch machine for operating said track switch; a detector track circuit associated with said track switch and including a track relay; a signal for governing the movement of trains over said track switch; a control relay for controlling said signal; a source of current in said dispatcher's office; an indicating relay in said dispatcher's office; a circuit including said source, said control relay and said indicating relay in series; means in said circuit at said distant track switch for opening said circuit continuously during occupancy of said track circuit to effect a corresponding deenergization of said indicating relay; and indicating means controlled by said indicating relay.
11. In a dispatching system, the combination with a local dispatcher's office and a railway system having a distant track switch; of a switch machine for operating said track switch; a detector track circuit associated with said track switch and including a track relay; a signal for governing the movement of trains over said track switch; a control relay for controlling said track switch and signal; a source of current in said dispatcher's office; an indicating relay in said dispatcher's office; a circuit including said source, said control relay and said indicating relay in series; means in said circuit at said distant track switch for opening said circuit so long as said track circuit is occupied to effect a corresponding deenergization of said indication relay so long as said track circuit is occupied; and indicating means controlled by said indicating relay.
12. In a dispatching system, the combination with a local dispatcher's office and a railway system having a distant track switch; of a switch machine for operating said track switch; a detector track circuit associated with said track switch and including a track relay; a signal for governing the movement of trains over said track switch; a control relay for controlling said track switch and signal; a source of current in said dispatcher's office; an indicating relay in said dispatcher's office; a circuit including said source, said control relay and said indicating relay in series; means in said circuit at said distant track switch for opening said circuit during occupancy of said track circuit to effect a corresponding deenergization of said indication relay; and two indicators controlled by said indicating relay one indicator of which is rendered effective so long as said indicating relay is deenergized and the other indicator of which is effective until manually released even though said indicating relay has been energized in the meantime.
13. In a dispatching system, the combination with a local dispatcher's office and a railway system having a distant track switch; of a switch machine for operating said track switch; a detector track circuit associated with said track switch and including a track relay; a signal for governing the movement of trains over said track switch; a control relay for controlling said track switch and signal; a source of current in said dispatcher's office; an indicating relay in said dispatcher's office; a circuit including said source, said control relay and said indicating relay in series; means in said circuit at said distant track switch for opening said circuit during occupancy of said track circuit to effect a corresponding deenergization of said indication relay; and indicating means controlled by said indicating relay.

- switch and including a track relay; a signal for governing the movement of trains over said track switch; a control relay for controlling said track switch and signal; a source of current in said dispatcher's office; an indicating relay in said dispatcher's office; a circuit including said source, said control relay and said indicating relay in series; means in said circuit at said distant track switch for opening said circuit during occupancy 5 of said track circuit to effect a corresponding de-energization of said indication relay; a stick relay picked up upon deenergization of said indicating relay and having a stick circuit including a manually operable contact, and two indicators 10 one of which is effective when said indicating relay is deenergized and the other of which is effective when said stick relay is energized.
14. In a dispatching system, the combination with a local dispatcher's office and a railway system 15 having a distant track switch; of a switch machine for operating said track switch; a detector track circuit associated with said track switch and including a track relay; a signal for governing the movement of trains over said track switch; a control relay for controlling said track switch and signal; a source of current in said dispatcher's office; an indicating relay in said dispatcher's office; a circuit including said source, said control relay and said indicating relay in 20 series; means in said circuit at said distant track switch for opening said circuit during occupancy of said track circuit to effect a corresponding de-energization of said indicating relay; a stick relay picked up upon deenergization of said indicating relay and having a stick circuit including a contact closed only when a lever in said office 25 is in a position to apply said source to said control relay, and two indicators one of which is effective when said indicating relay is deenergized and the other of which is effective when said stick relay is energized.
15. In combination, a railway traffic governing device, a motor for driving said device between two extreme positions, a normally closed 30 circuit controlling means controlled by said device and arranged to be opened for a brief interval during operation of said device, a slow-releasing relay for controlling said motor, a quick-releasing relay, an indicator controlled by said quick-releasing relay, and a circuit including said two relays and said circuit controlling means.
16. In combination with a railway switch, a 35 slow-releasing polarized relay, means for shifting said switch to its normal or reverse position according as the polarized relay is energized in the normal or reverse direction, means for supplying current of one polarity or the other to said polarized relay, an indication relay interposed in series with said polarized relay, and means effective during operation of said switch to break the circuit including said two relays for a time interval long enough to de-energize said indication relay but not said polarized relay.
17. In combination, a railway traffic governing device, a polarized relay for controlling said device, a manually operable lever located at a point remote from the switch for controlling said 40 polarized relay over a single pair of wires, an indication relay interposed in one of said wires and located adjacent said lever, and means controlled by said device for at times opening the circuit for said polarized relay to de-energize said indication relay for an interval of time too brief to allow said polarized relay to become de-energized.
18. In combination with a railway traffic governing device, a first relay for controlling said device, an indication relay, a manually operable lever, means controlled by said lever for at times supplying current to said two relays in series, means controlled by said device for at times opening said indication relay for a brief interval without opening said first relay, and means operating under certain conditions of traffic adjacent said device for continuously opening both said relays.
19. In combination, a railway traffic governing device, a first relay for controlling said device, an indication relay, a manually controlled circuit for at times supplying current to said first relay and said indication relay in series, and means responsive to an operation of said device for interrupting said circuit for a time interval sufficient to open said indication relay but not sufficient to open said first relay.
20. In combination with a railway traffic governing device, a slow acting relay for controlling said device, a quick acting relay, a manually controlled lever, a circuit controlled by said lever and including said two relays in series, and means controlled by said device for at times interrupting said circuit for an interval of time sufficient to open said quick acting relay but not said slow acting relay.

FRANK LAMONT DODGSON.
